UNITED STATES PATENT OFFICE.

THOMAS MARION DANIELS, OF CHICAGO, ILLINOIS.

LOCK-NUT.

1,265,752.

Specification of Letters Patent. Patented May 14, 1918.

Original application filed July 8, 1915, Serial No. 38,680. Divided and this application filed March 20, 1917. Serial No. 155,982.

To all whom it may concern:

Be it known that I, THOMAS MARION DANIELS, a citizen of the United States, and a resident of Chicago, in the county of Cook and State of Illinois, have invented certain new and useful Improvements in Lock-Nuts, of which the following is a specification.

My invention has reference to that type of lock nut capable of being flexed whereby 10 to lock with a conventional nut when wrenched down upon the same; and in this connection contemplates as a matter of economy and ease in manufacture the utilization of the ordinary tapped blank usually 15 cut or punched in a number from a flat metal strip of uniform thickness prior to the tapping operation.

One of the main objects of the invention is to provide means on such a blank adapted 20 when associated with a bolt and a conventional nut to act as fulcra at two diametrically opposite corners, and in such a way as to also serve as spacing members for spacing the nuts apart so that when the lock nut is 25 wrenched a flexure of its body will occur into the space between the fulcra and on a line intermediate the corners not so provided, whereby insuring a full measure of spring reaction on the bolt and a maximum 30 jamming effect between the threads of the bolt and the lock nut.

My invention also contemplates the provision of a lock nut of the character described which operates equally well on flat 35 surfaces and on irregular surfaces, such as rounded or sloping faces, thereby materially increasing the range of usefulness of the nut, reducing the number of sizes, simplifying manufacture, and reducing the cost.

Another object in so providing the nut is that all flexing or bending stress is transferred to corner portions of the nut where the most metal occurs, and not to side portions of the nut, where the metal is relatively thinner, and which would create a tendency toward breakage or weakening of the nut structure. My invention therefore has in contemplation the improving of the construction and the increasing of the efficiency, utility, and compactness of devices of the type; and provides for the forming of the fulcra and spacing members, and on both faces of the nut, though oppositely disposed thereon, by a partial punching or abrupt 50 placement of small bosses of metal from the

web of the blank, with each boss depending below the face of the nut substantially intermediate the bore and the corner angle formed by the wrenching side faces of the blank.

Again, it is the purpose of my invention 60 to provide lock nuts such as described, which can be nested in compact form for shipping and storage purposes.

These, together with such other objects as hereinafter appear, or are incident to my 65 invention, I attain by means of the construction illustrated in preferred form in the accompanying drawing, wherein:—

Figure 1 represents a view in perspective of my improved lock nut; Fig. 2 is a view in 70 elevation showing the lock nut in wrenched position; and Fig. 3 is a vertical section taken through the nut intermediate its corners and through the bore.

As will be seen from an inspection of the 75 drawings, my lock nut has its body portion 10 centrally tapped at 11, and has bosses 12 formed on its under face at diametrically opposite corners to depend appreciably below said underface. To attain reversibility 80 of the nut the upper face is similarly provided with bosses 12^a, though on different corners. As illustrated, the body 10 is desirably flat and of uniform thickness, the bosses being each formed from a portion of 85 the metal punched out or displaced from the web within a corner, leaving the rest of the metal about the annular recess 13 and the boss undisturbed.

In practice, a plain nut A is first screwed 90 home on the bolt B and against a structure C, after which the lock nut is in turn screwed home on the bolt with the bosses 12 taking against the beveled upper faces of the nut A. When thus positioned, the 95 bosses space the nuts wholly apart, and continued screwing or wrenching of the lock nut forwardly by means of a wrench causes the center to be sprung into this space along a line extending intermediate the corners 100 unprovided with the bosses 12, the degree of flexure being determined by the extent of forward movement of the lock nut on the bolt B. This flexure of the nut causes the screw threads of the bolt and the lock nut 105 to jam within the nut, and operates to lock the plain nut against any tendency to turn or back off the bolt.

In so forming my nut, the bosses depend 110 appreciably below its under face and cor-

ners, providing points of fulcrum intermediate the bore and diametrically opposite corners of the nut, and furthermore serving to maintain a space under all conditions of use into which the body portion of the nut may bend during the wrenching of the nut.

It will be seen from the foregoing that my improved nut is so constructed that it operates equally well on plain or flat surfaces, or on 10 irregular surfaces such as sloping or curved surfaces. Thus for example, my improved lock nut will lock a nut which has plain faces or it will lock a nut the outer face of which is curved, as is frequently the case. It will 15 be clear that the bosses, which depend or project appreciably from the faces of the lock nut, will serve to flex the lock nut when the nut is applied to either kind of surface. It will also be seen that the nuts may be 20 nested, that is, assembled with the bosses on one side of one nut projecting into the corresponding recesses of the adjacent nut. Thus for shipping and storing purposes it will be seen that the nuts occupy no more 25 space than would be the case if they were plain on both faces. Again, it will be seen that the construction is such as to obtain a maximum degree of flexing.

What I claim is:

- 30 1. A lock nut provided with a threaded

aperture and having upon each face a plurality of bosses remote from the edge of the nut and located between said edge and said aperture, said bosses being oppositely disposed and adapted to effect a distortion of 35 the nut and its threads when the nut is screwed down upon the proximate structure, substantially as described.

2. A device of the class described comprising a threaded reversible lock nut provided 40 upon each face with a plurality of bosses struck from the stock and having rounded engaging points adapted for engagement with the proximate structure whereby, when the nut is screwed down 45 upon the bolt, said points will engage said structure and effect a distortion of the nut and its threads, substantially as described and for the purposes set forth.

3. An apertured lock nut provided upon 50 each face with two oppositely disposed rounded bosses and two oppositely disposed depressions having rounded walls, each boss on each face being in alinement with a depression on the opposite face, whereby the 55 lock nuts may be nested for shipping and storing purposes, substantially as described.

In testimony whereof I have hereunto signed my name to this specification.

THOMAS MARION DANIELS.
